HOLDER FOR SLIDES FOR MICROSCOPE USE

Richard A. Brumbach, 4845 W. 220th St.,
Fairview Park, Ohio

Filed May 24, 1962, Ser. No. 70,255

Term of patent 14 years

(Cl. D61—1)

FIG. 1

FIG. 2

FIG. 4

FIG. 3

FIG. 5

FIG. 1 is a top plan view of a holder for slides for microscope use showing my new design;

FIG. 2 is a side elevation of the holder;

FIG. 3 is an end view of the holder;

FIG. 4 is a partial vertical longitudinal section through the holder taken as indicated by section line 4—4 of FIG. 1; and

FIG. 5 is a transverse vertical section taken through the holder on section line 5—5 of FIG. 1.

I claim:

The ornamental design for a holder for slides for microscope use, substantially as shown.
